CLAIM

The ornamental design for a non-conducting light bulb socket remover, as shown and described.

DESCRIPTION

FIG. 1 is a perspective view of a non-conducting light bulb socket remover showing my new design;

FIG. 2 is a front elevational view thereof, the left, right, and rear elevational views being a mirror image;

FIG. 3 is a top plan view; and,

FIG. 4 is a bottom plan view.

The broken line showing the environmental structure of the non-conducting light bulb socket remover is for illustrative purposes only and forms no part of the claimed design.

FIG. 1

FIG. 2

FIG. 3

FIG. 4
